UNITED STATES PATENT OFFICE.

JOHN E. CROWELL, OF UNION COUNTY, NORTH CAROLINA.

AUTOMATIC ADVANCING-GEAR.

1,229,893.

Specification of Letters Patent. Patented June 12, 1917.

Application filed July 15, 1916. Serial No. 109,486.

To all whom it may concern:

Be it known that I, JOHN E. CROWELL, a citizen of the United States, and a resident of Union county, in the State of North Carolina, have invented a new and useful Improvement in Automatic Advancing-Gear, of which the following is a specification.

My invention relates to improvements in internal combustion engines, and more particularly to cam shaft gears, and it consists in the constructions, combinations, and arrangements herein described and claimed.

An object of my invention is to provide a gear for the cam shaft of an internal combustion engine whereby the valves may be prematurely opened when the engine speeds up, in order to derive the full benefit of the power of the engine.

Other objects and advantages will appear in the following specification, reference being had to the accompanying drawings forming a part thereof, and in which:

Figure 1 is a diagrammatic vertical cross section of an engine illustrating the action of my device on the exhaust valve of the engine.

Fig. 2 is a cross section on the line 2—2 of Fig. 1.

Fig. 3 is an elevation of the device showing the parts in a normal position.

Fig. 4 is a similar view showing the parts as positioned in Fig. 1.

Fig. 5 is a detail perspective view of one of the centrifugal members.

By reference to Fig. 1 it will be observed that my device is embodied in an internal combustion engine of the usual type, which includes the crank shaft 1 and a cam shaft 2. The cam shaft carries a cam 3 with which the roller 4 of the exhaust valve stem 5 engages. It may be stated that in some engines of modern construction, the exhaust and inlet valve cams are carried by one shaft as shown in Fig. 1 of the drawings. The device is, however, applicable to motors having separate inlet and exhaust valve operating cam shafts, and in such instances one of the cam shaft gears is mounted on each shaft.

Mounted on the crank shaft 1 is a crank 6 with which the connecting rod 7 is joined. The connecting rod 7 carries the working piston 8 which reciprocates in the cylinder 9 of the engine. Carried by the crank shaft 1 is a pinion 10. The pinion 10 meshes

with the rim gear 11 which comprises an essential part of my invention. Secured to the end of the cam shaft 2 by screw bolts 12 is a cover plate 13. The cover plate 13 has an annular flange 14 forming a shoulder 15 in which the rim gear 11 is supported. By reference to Figs. 1, 2 and 4, it will be observed that a pair of centrifugal members 16 and 17 respectively, are mounted on the cover plate 13.

The centrifugal members 16 and 17 are pivotally mounted on the cover plate 13 by screw studs 18 which support the centrifugal members. Each of the centrifugal members 16 and 17 is provided with a flange 16^a and 17^a, a shoulder 16^b and 17^b being formed at the juncture of the respective flanges with the bodies of the centrifugal members. The remaining portion of the rim gear 11 rests in the respective shoulders 16^b and 17^b as shown in Fig. 2, thereby supporting the rim gear 11 equally on the bodies of the centrifugal members and the body of the cover plate 13. The centrifugal members 16 and 17 are adapted to swing outwardly when the speed of cam shaft 2 becomes excessive, as will presently be more fully explained.

The centrifugal members 16 and 17 are provided with notches 16^c and 17^c at places approximately diametrically opposite to the fulcrum studs 18. The rim gear 11 is provided with single teeth 20 at diametrically opposite points and these teeth 20 loosely engage the notches 16^c and 17^c as shown in Figs. 3 and 4. The purpose of the notches and the teeth 20 is to obviate any undue movement of the centrifugal members 16 and 17 when they are in an extended position, as shown in Fig. 4.

Secured to the edge of each of the centrifugal members 16 and 17, is a leaf spring 21. The leaf spring 21 is mounted in a suitable recess 22 in the edge of each of these members 16 and 17, so that when the centrifugal members are extended as shown in Fig. 4, the springs which will then be compressed will be seated within the recesses, while the edges of the centrifugal members bear against the inner periphery of the rim gear. While I have shown the leaf springs 21 as being secured to the centrifugal members at a central point, other types of springs may be employed. The purpose of these springs 21 is to act as buffers for the centrifugal members 16 and 17 when they move

outwardly under centrifugal action to the position shown in Fig. 4.

Having now described the construction of my device, the operation thereof is as follows: In the ordinary practice of assembling the valve actuating mechanism of an internal combustion engine, it is customary to set the crank 6 approximately one half of an inch from the extremity of its down stroke, as indicated at the point *a* in Fig. 1, while the exhaust cam 3 will be in such a position as to begin to operate the exhaust valve 5. The purpose of this setting is to open the exhaust valve early enough when the engine is traveling at fast speed.

With the automatic advancing gear attached, when the engine is running at slow speed, the inlet valves are caused to open late and in effect produce a greater suction. I have also observed in actual practice that the engine is capable of being cranked more easily. This is so because of the fact that the valves are set in a retarded position in the first instance, as previously explained. It therefore follows as above stated, that the piston will traverse a greater distance down the cylinder before the inlet valve will open. A greater suction is thereby caused, serving to draw in a greater volume of gas.

In assembling an engine embodying my invention, I set the crank 6 at the point *b* in Fig. 1, which is approximately one-eighth of an inch of the extremity of the outward or exhaust stroke of the piston, while the cam 3 is set so the valve will begin to open. The purpose of this arrangement will presently be made clear.

Let it now be assumed that the engine speeds up. The centrifugal members 16 and 17 will begin to move outwardly in the direction of the arrows *c* in Fig. 3. In moving outward, the centrifugal members 16 and 17 will rotate on the studs 18 in a counter-clockwise direction, indicated by arrow *d* in Fig. 3, until the position is reached as shown in Fig. 4. The centrifugal members 16 and 17 are fully extended in this position. In having moved from the position shown in Fig. 3 to that shown in Fig. 4, the fulcrum pins carried the cover plate 13 in the same direction, since, as previously stated and shown in the drawing, the cover plate and the centrifugal members are connected thereby. Since the action just explained was accomplished by the centrifugal force generated by the accelerated speed of the cam shaft 2, it follows that since the cover plate 13 is joined with the cam shaft 2, the cam shaft 2 will be slightly advanced. Assuming the crank 6 to be at the point *e* in Fig. 1 and the accelerated speed of the cam shaft occurring at this time, the cam 3 will be moved from the dotted position shown in Fig. 1, to the full line position indicated when the exhaust valve 5 will be

lifted and the products of the combustion be permitted to prematurely escape. The cylinder 9 of the engine will thus be emptied earlier. Since the action of the cam 3 is thus advanced when the engine is running at high speed, I have discovered from practice that the engine will develop more power, since the cylinder is emptied earlier, thus permitting the compressing of a new charge in a cleaner atmosphere, more efficient service of the engine being rendered.

My invention is also adapted for driving magneto shafts. In the usual construction of magnetos, the spark timing mechanism is mounted on the magneto casing, and an operating rod is conducted to the spark lever on the steering wheel. The spark is advanced and retarded by moving the spark lever back and forth. When my device is applied, however, the spark lever and connecting rod are dispensed with. The cover plate 13 with its associated members is then secured to the end of the magneto shaft, similarly as shown in Fig. 2. The timing of the spark is then varied by the action of the centrifugal members 16 and 17 by allowing the spark to occur earlier or later depending on the speed of the engine, and the position of the magneto armature is not required to be changed with relation to the magnetic pole pieces.

While the constructions and arrangements described are those of a preferred form, obviously various modifications may be made without departing from the spirit of the invention or the scope of the claims.

I claim:

1. In an internal combustion engine, the combination with the crank shaft and the cam shaft for operating the valves, of gearing connecting the two shafts and including a rim gear, a plate fast with the cam shaft to rotate therewith, and having the rim gear mounted thereon, and centrifugally operated members pivoted at one of their ends to the said plate, and having their opposite ends loosely connected with the rim gear, said members acting to advance the cam shaft in the direction of its rotation upon acceleration of the speed of the engine.

2. In combination, a rotary driving member, a rotary driven member geared to the rotary driving member, a rotary valve operating member mounted co-axially with the rotary driven member, a cover plate attached to the rotary valve operating member and having the said rotary driven member mounted thereon, and centrifugally operated means mounted on the cover plate and forming direct connecting means between the said cover plate and rotary driven member for advancing the latter.

3. In combination, a rotary driving member, a rotary driven member geared to the rotary driving member, a rotary valve op-

erating member in axial alinement with the rotary driven member, and centrifugally operating means having pivotal connection with the valve operating member, and a limited loose connection with the rotary driven member to advance the valve operating member in the direction of rotation of the driven member.

4. In combination, a rotary driven member, a rotary valve operating member disposed co-axially with the driven member, a cover plate attached to the valve operating member and having the rotary driven member mounted thereon, a centrifugally operated member mounted on the cover plate and having one end pivotally connected thereto and having its opposite end loosely connected to the said rotary driven member.

5. In combination, a rotary valve operating member, a disk rotatable with the valve operating member, a rotary driven member mounted on the disk, and centrifugally operated connecting means between the disk and the driven member to advance the valve operating member in the direction of rotation of the rotary driven member.

6. In an internal combustion engine, the combustion of a crank shaft having a driving pinion, a cam shaft, a rim gear associated with the cam shaft, a cover plate secured to the cam shaft and supporting the rim gear, segments fulcrumed on the cover plate, and means associated with the segments and rim gear for advancing the cam shaft in the direction of its rotation when the segments move under centrifugal action.

7. In an internal combustion engine, the combination of a crank shaft having a driving pinion, a cam shaft, a rim gear, a cover plate secured to the end of the cam shaft and

supporting the rim gear, segments fulcrumed on the cover plate in association with the rim gear, each of the segments having a notch, and a tooth projecting from the rim gear into each of the notches, said tooth and notch engagement acting as a pivotal point for the segments when the segments are acted on by the centrifugal force of the rotation of the cam shaft.

8. In an internal combustion engine, the combination of a crank shaft having a driving pinion, a cam shaft, a rim gear, a cover plate secured to the end of the cam shaft and supporting the rim gear, segments fulcrumed on the cover plate in association with the rim gear, each of the segments having a notch, and a tooth projecting from the rim gear into each of the notches, said tooth and notch engagement acting as a pivotal point for the segments when the segments are acted on by the centrifugal force of the rotation of the cam shaft, and means for retarding the outward movement of the segments.

9. In an internal combustion engine, the combination of a rotatable cam shaft, a cover disk secured to the end of the cam shaft having an annular shoulder, a rim gear partly supported on said shoulder, said rim gear having inwardly projected and diametrically opposite teeth, segments fulcrumed on the cover plate and having shoulders adapted to engage the rim gear, each of the segments having a notch for engagement with a tooth, said engagement acting as a pivotal point, and buffer springs mounted on the segments and engaging the rim gear for retarding the outward movement of the segments on their pivotal points under centrifugal action.

JOHN E. CROWELL.
